UNITED STATES PATENT OFFICE.

MARIE LOUIS ROLLIER, OF VANNES, FRANCE, ASSIGNOR TO CHARLES MARIE ANTOINE RIVOAL, OF PARIS, FRANCE.

MICROMETER-GAGE.

1,158,721.

Specification of Letters Patent.

Patented Nov. 2, 1915.

Application filed November 19, 1913. Serial No. 801,871.

To all whom it may concern:

Be it known that I, MARIE LOUIS ROLLIER, a citizen of the Republic of France, residing at Vannes, Seine, France, have invented 5 certain new and useful Micrometer-Gages, of which the following is a specification.

This invention relates to improved micrometer gages for taking accurate measurements, the said improvements tending to secure 10 with more precise results easier and quicker manipulation.

A micrometer gage in accordance with this invention comprises a movable dial arranged in front of a vernier, and caused to 15 be rotated by means of a plunger carrying a roller which bears on a cam whose contour has the shape of an Archimedean spiral, the said cam being mounted on the same spindle as the dial so that when the plunger 20 is acted upon, the roller permits the rotation of the cam which operates the dial.

The object of the invention consists essentially, in doing away with the thrust of the roller on the cam, by moving the said 25 cam by means of a spiral spring so that the roller carried by the plunger has only to maintain the cam in position against the action of the spiral spring, and the said cam will, when it is released by depressing the 30 plunger, rotate automatically while remaining in contact with the roller. This arrangement, which in reality is an indirect control while at the same time facilitating the manipulation and permitting of obtaining 35 a greater precision, obviates a premature wear of the cam and the roller and any tendency to jam which may occur.

In order to increase the range of the measurements of which the gage is susceptible 40 the plunger is made in two parts, one of which can slide within the other and be fixed in position by a bayonet joint arrangement.

The following description with reference 45 to the accompanying drawings illustrates a micrometer gage according to this invention which will enable the same to be readily understood, but the invention is not limited to the precise arrangement shown.

50 Figure 1 is a longitudinal section of the apparatus. Fig. 2 is a section on a longitudinal plane at about right angles to plane of Fig. 1, the line 1—1 in this view shows the plane of Fig. 1. Fig. 3 is a horizontal 55 section. Fig. 4 is an external view of the

case which contains the mechanism and shows the dial and vernier. Figs. 5 and 6 show respectively an elevation and horizontal section through line 2—2 of Fig. 5, of the sliding plunger, while Fig. 7 is a modification of the said plunger.

The cam *a*, the contour of which is an Archimedean spiral, is subjected to the action of a spiral spring *b* (Figs. 2 and 3) secured at one end to the said cam and at the other end to the arbor *c* on which the said cam is mounted and tending to turn the cam in the direction of the arrow 1 (Fig. 1). A roller *d* secured to the end of an arm *e* carried by the plunger *f* normally engages 70 (that is when the spiral spring is under tension) in a recess *g* provided in the cam *a*. A spring *h* connecting the arm *e* to the casing *i* of the gage maintains the plunger and cam, through the medium of the roller *d*, 75 in the position shown in the drawing, which position corresponds to the zero mark of the gage.

It will be readily understood that when the plunger is depressed the spring *h* is extended and the roller *d* gradually releases the cam *a* which turns automatically under the action of the spiral spring *b* while remaining in contact with the roller, until the arm *e* reaches the bottom of the casing when 80 the roller *d* assumes the position *d'*, so that while a measurement is being taken, the only pressure exerted by the arm on the roller is that due to the twisting moment of the spring. When the plunger is released the 85 spring *h* returns automatically to its initial position and the roller *d* following the contour of the cam causes the latter to turn in the reverse direction and come back to its original position, the spiral spring being 90 thereby wound up. The operator reads on the dial *j* and vernier *k* (Fig. 4) the measurement corresponding to the extent to which the plunger has moved downward.

The plunger consists preferably of two parts which permit of varying its stroke and consequently altering as desired the range of measurements of the gage. It consists of a sheath *f* slotted at *r* so as to allow the passage of the part of the cam *a* which has the larger radius and in the said sheath slides a rod *l* which constitutes the plunger proper (Figs. 5, 6, 7). The sheath *f* is provided at its upper part with the groove *m* of a bayonet joint while the rod *l* has a 110

lug *n* which can move in this groove. In the normal position, the lug *n* being out of the groove bears on the upper part of the sheath the edge of which presents a slope 5 while at the same time a washer *o* on the lower end of the rod *l* bears likewise on the other end of this sheath so that the rod is maintained in a fixed position, the lug *n* being jammed on the aforesaid slope so as 10 to press the washer *o* against the sheath, thereby avoiding all play and taking up the wear.

The groove *m* can be provided either with a single notch *p* at one end of the said 15 groove as shown in Fig. 5, or with several notches at various parts of its length, for instance it may be arranged as shown in Fig. 7, according to which it is provided with a notch *p* at the middle of its length 20 opening into the slotted part of the sheath. The notched part *p* and the lower edge of the part *f'* of the sheath are constituted as slope and counter slope so as to cause either the washer or the underside of the 25 plunger to bear on the sheath as hereinbefore explained and consequently do away with all play.

By displacing the rod *l* so that the lug *n* slides in the groove *m* and catching this lug 30 into the notch *p* or below the portion *f'* of the sheath at *p'*, the part of the plunger forming the movable measuring end of the gage is more or less lengthened, the initial space comprised between this movable measuring point and the fixed measuring part *q* 35 is accordingly modified so that the range of measurements of which the gage is susceptible can be varied as desired. The casing is shown internally of circular form and the 40 frame of horse-shoe shape. A set screw *m* is shown for holding the plunger in an advanced position either for ease in transportation or to enable the device to be used as a fixed gage.

45 What I claim is:—

1. In a micrometer gage, the combination with an indicating device, of a cam fast therewith, spring means continuously tend-

ing to turn the cam in one direction, a spring retracted plunger provided with an 50 engaging face continuously in contact with the cam, the cam being of such contour that extension of the plunger against the action of its spring permits the cam to move forwardly responsive to its spring and retraction of the plunger responsive to its spring 55 moves the cam backwardly against the action of its spring.

2. In a micrometer gage the combination with a cam, of a dial movable therewith, a 60 spring for turning the dial forwardly, a plunger having an engaging face for engaging the cam and permitting the forward movement of the dial upon its depression and for returning the cam and winding up 65 the cam spring upon its retraction.

3. In a micrometer gage the combination with a cam, of a dial movable therewith, a 70 spring for turning the dial forwardly, a plunger having an engaging face for engaging the cam and permitting the forward movement of the dial upon its depression and for returning the cam and winding up 75 the cam spring upon its retraction, and spring means for retracting the plunger. 75

4. In a micrometer gage the combination with a cam having the contour of an Archimedean spiral, of a dial movable with the cam, spring means for rotating the cam in the direction in which its radius decreases, a spring pressed actuator engaging the contour of the cam and holding it against the influence of its spring and located in position for releasing the cam to the influence of its spring upon its depression, and for returning the cam and winding up the cam spring upon its retraction 80 irresponsive of its own spring. 85

In witness whereof, I have hereunto signed my name in the presence of two sub- 90 scribing witnesses.

MARIE LOUIS ROLLIER.
